WAISTBAND STRUCTURE

Samuel F. Stein, Milton, Pa.

Application August 19, 1948, Serial No. 45,109

3 Claims. (Cl. 2-236)

1

My invention relates to garments and in particular it pertains to trousers that are supported at the waist of the wearer by a belt passing through a series of belt loops provided at the waist portion of the trousers.

In the drawings:

Fig. 1, illustrates a perspective view of a waist portion of trousers turned inside out with an inner belt applied thereto;

Fig. 2, illustrates a perspective view of the belt engaging loop shown in Fig. 1;

Fig. 3, is a cross section on line 3—3 of Fig. 1;

Fig. 4, illustrates a modified construction;

Fig. 5, is a cross section on line 5—5 of Fig. 1;

Fig. 6, is a cross section on line 6—6 of Fig. 4;

Fig. 7, illustrates a side pocket blank ready to be applied by the usual sewing machine operation to the front part of the trousers and to be formed into a side pocket thereof.

As trousers are commonly made they come in an assortment of waist measurements, and trousers having a certain waist measurement are tailored to fit in accordance with various leg measurements to suit the purchaser of the trousers. The difference between the maximum and minimum leg lengths to which the trousers may be altered is approximately seven inches, and in a lot of trousers having the same waist measurement and the same measurement from the crotch to the top of the trousers, called the "rise," some may be tailored to fit a person requiring, say: 34 inches in length, while others may be altered to 27 inches in length and various leg lengths between, the rise however remains the same. The consequence is that the trousers which have been altered for a short-legged person will not fit the wearer properly over the hips, and the belt encircling the waist of the wearer with the waist portion of the trousers will drop to a lower position on the wearer's body, producing unnecessary fulness at the crotch, causing the wearer's legs to appear shorter as well as producing an undesirable effect at the bottom of the trousers legs.

Trousers as are customarily made are provided with belt loops that reach substantially to the top edge of the band of the trousers, while some are equipped with loops that are placed at a point below the top of the trouser band, called "dropped loops," intended to meet with the requirement of a person with lower hips. However, it is limitary how far the loops may be dropped, for the sake of appearance. The "dropped loop" construction also has the disadvantage that when a belt is worn through such loops the band of the trousers becomes wrinkled and untidy and the waist band lining is exposed, which is undesirable.

2

My invention contemplates the provision of belt-engaging means within the waist portion of the trousers, whereby a suitable belt may be worn inside of the trousers and which belt would be positioned at a point lower than that which could be obtained by the employment of the ordinary belt loops described above, and the inner belt referred to may be wide as well as narrow as desired to better fit the hips of the wearer, as appearance is not pertinent in this case. The belt in accordance with my invention of the belt-engaging means inside the waist portion of the trousers may be fabricated of any suitable material, elastic or non-elastic, and may be removed from the trousers during the process of dry cleaning or washing the trousers, if desired.

Referring to the drawings. 10, illustrates the waist portion of a pair of trousers; 11, is the hip pocket material; 12, is the side pocket material; 13, is the waist band of the trousers; 14, are the customary loops; 15, is the waist band lining; 16, is a line of stitching securing said waist band lining in position at the lower edge of said waist band, and extending from said line of stitching 20 there is a substantially narrow folded-over extension 17; 18, is a tunnel loop secured at its free ends in position under extension 17; said tunnel loop 18 has an opening 19, to permit the passage of belt 20 through it; said opening is made sufficiently large to accommodate wide belts as well as narrow belts; 21, is another tunnel for the passage of belt 20. I am showing in this case the utilization for the tunnel the upper extension 22 of the hip pocket material 11, but in order to accomplish this result the arrangement is such that the belt loops 14, when being tacked onto the trouser material are not tacked to any part of extension 22, which would cause belt 20 to be hindered from passing freely through tunnel 21. This arrangement can be accomplished by moving extension 22 out of the way when loops 14 are being tacked to the trouser material, or the respective positions of the loops may be carefully arranged to overcome any likelihood of obstructing the free passage through tunnel 21. However, a tunnel loop similar to 18 may be employed in connection with hip pocket 11, and the question of tacking the loops would not be a problem to be solved.

As shown in Fig. 4, the construction is similar to what is illustrated in Fig. 1, with exception that I utilize the upper portion of the side pocket as a belt-receiving tunnel loop in lieu of the tunnel loop 18, shown in Fig. 1. In order to make this possible certain novel features of construction are resorted to in the formation of the side pocket

material and the application of the latter to the trousers when the side pocket is finally completed in order to provide unobstructed means for the reception of the belt 20.

The waist portion of the trousers shown in Fig. 4, has "dropped loops" 26, instead of loops 14, shown in Fig. 1, and the belt 20, after passing through tunnel 21, passes through openings 23, 24 and 25, successively. In order to provide unobstructed means for the passing of belt 20 through the series of openings 23, 24 and 25, the tacking of the "dropped loops" at their lower ends would consequently have to be arranged to eliminate any interference with said openings, and that the upper portion 27 of side pocket 23 forming tunnel 29, does not become attached to the trouser material at the points where the belt loops 26 may be tacked.

As shown in Fig. 7, 30 illustrates a pocket material blank for the formation of a trouser side pocket; 31, is a pocket facing cut of the same cloth as the trouser material. The pocket facing 31, is sewed onto the pocket blank 30 by stitching 32, slightly spaced from the adjacent edge of said pocket blank and the upper end 33 of facing 31 is left detached from the pocket blank 30, a predetermined distance downward from said end edge and this detached space forms opening 24. Opening 25 is formed by cutting a slit at the upper end edge of the side pocket blank at a suitable point along the width thereof and folding over edges 34 towards the inside of the side pocket blank where said folded-over edges are suitably secured in position. When the side pocket is finally formed as a part of the trouser front part 35, said front part and the complementary back part 36 are joined by a seam 37, when the adjacent folded edge 38 of the side pocket material is sewed by stitching 39 to the adjacent edge 40 of part 36. Said folded edge 38 is left detached from the adjacent edge 40, to an extent corresponding with openings 24 and 25 and thus opening 23 is formed.

Instead of tunnel loops 18, narrower loops may be employed as belt-engaging means and as many belt-engaging loops as may be found desirable. The usual outer belt may be worn in addition to the inner belt described herein. The inner belt may be as wide as may be required for the purpose of supporting the trousers well from the hips of the wearer.

It will be seen that the line of stitching 16, which secures the waist band lining 15 to the body of the trousers, helps considerably to support the waist portion of the trousers on the body of the wearer, for the reason that the upper edge 41 of inner belt 20 acts as a base for the line of stitching 16 while the lower edge 42 is resting on the hips of the wearer and the waist band lining 15 at the line of stitching 16 engages the upper edge 41 of belt 20, in conjunction with the folded-over extension 17 of the waist band lining 15. When the upper belt 43 is worn in connection with lower belt 20, the combined width of the two belts forms a wide body-encircling member which in certain cases is very desirable to the wearer.

While I have described a preferred embodiment of my invention, it is understood that the same is susceptible of modification in various

forms without departing from the spirit and scope of my invention. I therefore desire that what I claim be given broad interpretation and be limited only by prior art pertaining thereto.

I claim:

1. Trousers having a waist portion comprising front and back parts, a lining attached to said waist portion by a line of stitching spaced substantially from the upper edge of said waist portion, a hip pocket attached to said back part having an extension extending upwardly to said line of stitching and secured therat, said extension producing belt-engaging means in form of a tunnel for the reception of a belt between the inner side of said extension and the adjacent material, belt-engaging means complementary to said tunnel associated with said front part of the trousers, said belt-engaging means extending downwardly in the inner side of the trousers whereby a body-encircling belt may be worn at a point substantially below the top of the waist portion of the trousers while another belt may be worn on the outer side of the trousers at a point above the location of the inner belt.

2. Trousers comprising a waist portion having a waist band extending downwardly from the top edge thereof to the inner side of the trousers and secured therat by stitching spaced substantially from the top edge of said waist portion, said trousers comprising hip and side pockets at the inner side, the hip pocket structure having an extension that extends upwardly to meet said waist band where said extension is secured, said extension comprising belt-engaging means and belt-engaging means associated with said side pocket structure, whereby a body-encircling belt may be worn at the inner side of the trousers at a point substantially below the top edge of the waist portion of the trousers.

3. Trousers comprising a waist portion having a waist band extending downwardly from the top edge thereof to the inner side of the trousers and secured therat by stitching spaced substantially from the top edge of said waist portion, pockets at the inner side of said trousers extending to and overlapped by the edge of said waist band and secured therat, belt-engaging means associated with the upper portions of said pockets adjacent to said waist band edge whereby a body-encircling belt may be worn at the inner side of the trousers at a point substantially below the top edge of the waist portion while another belt may be worn on the outer side of the trousers at a point above the inner belt.
